UNITED STATES PATENT OFFICE

HEINRICH ROHWER, OF KIEL, GERMANY, ASSIGNOR TO FRIED. KRUPP GERMANIA-
WERFT AKTIENGESELLSCHAFT, OF KIEL-GAARDEN, PRUSSIA, GERMANY

FUEL FEEDING VALVE

Application filed January 24, 1930, Serial No. 423,234, and in Germany February 7, 1929.

The invention relates to fuel-feeding valves of the needle type for internal combustion engines, more particularly Diesel engines.

In designing fuel-feeding valves of this type it is well-known to provide a special needle seat body having a shape like a plate and the conical shell surface of which is pressed by a screw cap with the necessary tightening pressure on to a corresponding 10 conical face of a needle guiding sleeve.

Upon the screw cap being unscrewed which is necessary for instance for cleaning the spray nozzle, this known needle seat body takes part in the unscrewing rotation and is 15 thus disconnected from the needle sleeve. Therefore, in re-assembling the needle seat body does not longer assume its original position relatively to the needle and needle sleeve, whereby leakage of the valve may be 20 caused.

Furthermore, in employing the known needle seat body it is a condition for a tight closure of the valve that the internal abutting face of the screw cap be always directed accurately normally to the needle. Already quite a deviation from this position will cause the needle seat body to not assume its 25 position determined by the conical tightening faces but to be tightened obliquely. The reason therefor is that owing to the plate shape of the needle seat body the narrow conical faces do not form a reliable straight guide but act like a ball joint, and that the 30 position of the needle seat body always depends upon the position of the internal face of the screw cap.

Now the object of the invention is to overcome these drawbacks which object is achieved by the fact that according to the invention the seat for the fuel needle consists 40 of a separate hardened tubular member which conically fits with adhesive friction in an extension of the needle sleeve and is pressed with the necessary tightening pressure into 45 this sleeve by means of a nozzle member that forms an abutment therefor and includes the spraying hole, so that an accurate central position of the needle seat is obtained.

In order that the invention can be more 50 readily understood, an embodiment of the

same is illustrated by way of example in the accompanying drawing which shows the lower portion of a fuel-feeding needle valve in longitudinal section.

A denotes the lower portion of the valve 55 casing, B the needle sleeve fitting therein, and C denotes the fuel needle. According to the invention the seat for the needle C is formed by an inserted tubular member D made of a suitable hardened material and conically 60 fitting in the extension of sleeve B with adhesive friction. The member D is held in position from outside by the nozzle member E and pressed into sleeve B with the required 65 tightening pressure by tightening home member E.

Fuel is supplied under high pressure through passage F and enters the annular chamber G above the needle seat.

When the needle C is lifted the fuel enters 70 the combustion chamber of the cylinder through the inserted member D and nozzle member E in the shape of separate jets.

When compared with known fuel needle valves in which needle sleeve and needle seat 75 are made in one piece the described design affords the advantage that the seat can be hardened very satisfactorily. Furthermore, it is possible when turning out the annular chamber G, to introduce the turning tool 80 through the extension of sleeve B so that a much shorter tool can be used whereby the turning work becomes more accurate. In comparison, further, with needle valves in which the needle seat is provided in the nozzle plate, the present arrangement affords the 85 advantage of the seat being capable of being centered more accurately owing to the tapered shape of the inserted member D.

What I claim and desire to secure by Letters Patent, is:—

1. A fuel valve comprising a casing, a valve needle therein, a guiding sleeve for said needle in said casing, an extension on said sleeve extending beyond the point of said needle, a 95 seat body for said needle firmly fixed in said extension by a pressed fit and projecting beyond it and adapted to remain fixed therein when the valve is disassembled, and a nozzle member adapted to be screwed on to said cas- 100

ing and to tighten thereby said seat body in said extension.

2. A fuel valve comprising a casing, a valve needle therein, a guiding sleeve for said needle in said casing, an extension on said sleeve extending beyond the point of said needle, a tubular seat body for said needle with a slight taper on its exterior firmly fixed in said extension by a pressed fit and projecting beyond it, and adapted to remain fixed therein when the valve is disassembled, and a nozzle member adapted to be screwed on to said casing and to tighten thereby said seat body in said extension.

10 3. A fuel valve comprising a casing, a valve needle therein, a guiding sleeve for said needle in said casing, an extension on said sleeve extending beyond the point of said needle, a cylindrical seat body for said needle firmly fixed in said extension by a pressed fit and adapted to remain fixed therein when the valve is disassembled, and a nozzle member adapted to be screwed onto said casing, abutting said seat body at the end opposite the

25 needle seat.

The foregoing specification signed at Hamburg, Germany, this 9th day of January 1930.
